F. P. HUNKLE & C. NORDFELDT.

METALLIC TIE AND RAIL FASTENER.

APPLICATION FILED JAN. 20, 1912.

1,024,939.

Patented Apr. 30, 1912.

UNITED STATES PATENT OFFICE.

FREDERICK P. HUNKLE AND CHARLES NORDFELDT, OF MCKEESPORT, PENNSYLVANIA.

METALLIC TIE AND RAIL-FASTENER.

1,024,939.

Specification of Letters Patent. Patented Apr. 30, 1912.

Application filed January 20, 1912. Serial No. 672,420.

To all whom it may concern:

Be it known that we, FREDERICK P. HUNKLE and CHARLES NORDFELDT, citizens of the United States of America, residing at Mc-
5 Keesport, in the county of Allegheny and State of Pennsylvania, have invented cer-
tain new and useful Improvements in Me-
tallic Ties and Rail-Fasteners, of which the
following is a specification, reference being
10 had therein to the accompanying drawing.

This invention relates to metallic ties and rail fasteners, and the primary object of our invention is to provide an extremely light and durable tie that can be manufactured at
15 a minimum cost, easily tamped in a road-
bed by unskilled labor, and used in lieu of the ordinary type of wooden tie.

Another object of our invention is to pro-
20 vide a tie possessing sufficient strength and firmness to support the great weight of roll-
ing stock and the requisite amount of elas-
ticity to prevent injury to rolling stock.

A further object of our invention is to furnish a metallic tie with fasteners that
25 can be repeatedly adjusted to compensate for wear and prevent lateral and vertical dis-
placement of rails mounted thereon.

A still further object of this invention is to provide rail fasteners that are durable,
30 inexpensive to manufacture and highly ef-
ficient for the purposes for which they are intended.

With the above and other objects in view, the invention resides in the novel construc-
35 tion, combination and arrangement of parts to be hereinafter specifically described and then claimed.

Reference will now be had to the drawing, wherein like numerals denote corre-
40 sponding parts throughout the several views, in which:—

Figure 1 is a top plan of a portion of a tie with one of the fasteners thereof partly broken away and partly in section, Fig. 2 is
45 a bottom plan of the same, Fig. 3 is a cross sectional view taken on the line III—III of Fig. 1, and Fig. 4 is an enlarged per-
spective view of a detached inner fastener.

A metallic tie in accordance with our in-
50 vention comprises longitudinal side walls 1 and 2 having the upper edges thereof connected by a top plate 3 that has lateral ex-
tensions 4 at the ends thereof and an ob-
long central opening 5. The ends of the
55 opening 5 are in communication with longi-
tudinal slots 6 and the top plate 3, adjacent

to said slots, is braced by transverse webs 7 formed integral with the top plate 3 and the side walls 1 and 2. The top plate 1, ad-
jacent to the ends thereof, is provided with 60 integral outer fasteners 8 in the form of splice bars of a greater length than the width of said top plate. The outer fas-
teners 8 are adapted to brace the outer sides of rails 9 placed upon said top plate, said 65 outer fasteners engaging the webs 10 and the heads 11 of said rails.

Retaining the rails 9 in engagement with the outer fasteners 8 are inner fasteners 12 of the splice bar construction, said inner 70 fasteners having pins 13 extending into openings 14 provided therefor in the webs 10 of the rails. The inner fasteners corre-
spond in length to the outer fasteners and the ends of said inner fasteners are pro- 75 vided with depending hooks 15 engaging under the lateral extensions 4 of the top plate 3. The inner fasteners 12, intermedi-
ate the ends thereof, are provided with lat-
eral extensions 16, and the under sides of 80 said extensions are flat to rest upon the top plate 3 and the top of said extensions gradu-
ally swelled or enlarged to brace the inner fasteners. The extensions have depending L-shaped members 17 reinforced by webs 85 18. Engaging the members 17 are tapering keys or wedges 19 that are driven between the webs 7 and said members to force the inner fasteners into engagement with the rails and to lock the inner fasteners in en- 90 gagement with the top plate 1. The tapering keys or wedges 19 are driven through open-
ings 20 provided therefor in the wall 1 of the tie, and the wall 2 of said tie, at a point opposite the openings 20, is provided with 95 openings 21 to accommodate screws 22 that enter the small ends of the keys or wedges 19 and retain said keys or wedges in en-
gagement with the tie.

The walls of the tie can be easily em-
bedded in the ballast of a roadbed, and the 100 large opening 5 permits of ballast being placed in the tie to firmly anchor the same, after the inner fasteners have been shifted into engagement with the rails and locked 105 in position. With the outer fasteners formed integral with the tie and the inner fasteners hooked under the lateral exten-
sions 4 of the tie, it is impossible for the fasteners to become vertically displaced, 110 while the pins 13 prevent longitudinal dis-
placement of said rails.

While in the drawing we have illustrated a preferred embodiment of the invention, it is to be understood that the structural elements thereof are susceptible to such changes as fall within the scope of the appended claims.

What we claim is:—

1. In a metallic tie and rail fastener, the combination with rails having the webs thereof provided with openings, of a tie having a top plate provided with a central longitudinal opening and longitudinal slots, outer rail fasteners formed integral with the top plate of said tie and bracing the outer sides of said rails, inner rail fasteners bracing the inner sides of said rails and having the ends thereof provided with hooks to engage under the longitudinal edges of the top plate of said tie, pins carried by said inner fasteners and extending into the openings of the webs of said rails, lateral extensions carried by said inner fasteners and extending over the slots in the top plate of said tie, and means located within said tie and adapted to lock said extensions in engagement with the top plate thereof.
2. In a metallic tie and rail fastener, the combination with rails, of a tie having a top plate provided with slots, outer fasteners carried by said tie for bracing the outer sides of said rails, inner fasteners bracing the inner sides of said rails and having the ends thereof provided with depending hooks to engage with the top plate of said tie, lateral extensions carried by said inner fasteners and extending over the slots in the top plate of said tie, depending L-shaped members carried by said extensions, and means arranged within said tie and engaging said members for locking said extensions upon said tie.
3. In a metallic tie and rail fastener, the

combination with rails, of a tie having the top plate thereof provided with slots, webs 45 bracing the top plate of said tie, outer fasteners carried by the top plate of said tie for bracing the outer sides of said rails, inner fasteners bracing the inner sides of said rails and having depending hooks engaging 50 under the longitudinal edges of the top plate of said tie, extensions carried by said inner fasteners, depending members carried by said extensions and extending into said tie, and means interposed between 55 said members and the webs of said tie for locking said inner fasteners upon the top plate of said tie and in engagement with said rails.

4. In a metallic tie and rail fastener, the 60 combination with rails, of a tie having the top plate thereof provided with slots, webs bracing the top plate of said tie, outer fasteners carried by the top plate of said tie for bracing the outer sides of said rails, inner fasteners bracing the inner sides of said rails and having depending hooks engaging 65 under the longitudinal edges of the top plate of said tie, extensions carried by said inner fasteners, depending members carried 70 by said extensions and extending into said tie, means interposed between said members and the webs of said tie for locking said inner fasteners upon the top plate of said tie and in engagement with said rails, said means including tapering keys having the small ends thereof locked in engagement 75 with one of the walls of said tie.

In testimony whereof we affix our signatures in the presence of two witnesses.

FREDERICK P. HUNKLE.
CHARLES NORDFELDT.

Witnesses:

MAX H. SROLOVITZ,
CHRISTINA T. HOOD.
